LLP

(57) CLAIM

The ornamental design for platform sandals as shown and described.

DESCRIPTION

FIG. 1 is a front view of the left sandal of the platform sandals according to my new design;

FIG. 2 is a rear view thereof;

FIG. 3 is a top view thereof;

FIG. 4 is a bottom view thereof;

FIG. 5 is a left side view thereof;

FIG. 6 is a right side view thereof; and,

FIG. 7 is a front-left-top perspective view thereof.

The right sandal is a mirror image of the left sandal and is not shown.
